UNITED STATES PATENT OFFICE.

FRANK N. REEVES, OF NEWARK, NEW JERSEY, AND ALBEN E. LUNDELL, OF NEW YORK,
N. Y., ASSIGNEES, BY MESNE ASSIGNMENTS, TO WESTERN ELECTRIC COMPANY,
INCORPORATED, A CORPORATION OF NEW YORK.

TELEPHONE-EXCHANGE SYSTEM.

1,212,809.

Specification of Letters Patent. Patented Jan. 16, 1917.

Application filed September 11, 1915. Serial No. 50,170.

To all whom it may concern:

Be it known that we, FRANK N. REEVES and ALBEN E. LUNDELL, citizens of the United States, residing at Newark, in the county of Essex and State of New Jersey, and at New York, in the county of Bronx and State of New York, respectively, have invented certain new and useful Improvements in Telephone-Exchange Systems, of which the following is a full, clear, concise, and exact description.

This invention relates to telephone exchange systems, and more particularly to selection controlling systems for automatic 15 or semi-automatic telephone exchanges.

This invention is preferably practised in connection with systems in which the establishment of a connection is controlled by what is known as the revertive impulse system of control: that is, in which the selecting operations are controlled and accompanied by impulses established in the selecting or fundamental circuit by the movement of a part of the selector, which impulses affect the sending or controlling apparatus until the proper number of impulses have been sent and the proper selection has been accomplished, when the controlling apparatus will in turn so affect the selector 25 under control that it will stop when the proper selection is made. Thus in systems of this character the impulses, instead of passing from the sending or controlling apparatus to the selector under control, pass 30 from the selector under control to the controlling apparatus.

According to an outstanding feature of this invention, a plurality of selector switches controllable from a sending station are controlled in their selective operation by a single relay associated with one of the selector switches.

The invention will be more fully understood by reference to the accompanying 45 drawings, wherein—

Figures 1, 2 and 3 taken together are illustrative of a system of circuits of a semi-automatic telephone exchange system embodying the invention; Fig. 1 representing 50 a calling telephone line and a part of an operator's connecting circuit equipment, Fig. 2 the circuits of a trunk selector, and Fig. 3 the circuits of a final selector and a called telephone line.

The following description of the system 55 illustrated in these drawings is written under the assumption that any form of selector mechanism and apparatus for the control thereof may be employed. In view of the fact that such equipment is not in itself 60 a feature of the invention, for the sake of simplicity most of the details thereof are omitted, and the various parts are not shown in their mechanical relation to each other.

The invention has been found useful in 65 connection with automatic switches of the panel type as disclosed, for example, in patent to Reynolds No. 1,058,903.

Assuming that a subscriber at station 100 is calling for a subscriber at station 300: 70 the operator first answers the call by inserting the plug 101 into the spring jack 102, then sets up on a well-known controlling or impulse receiving mechanism 103, the number representing the station wanted. Having set up the number, whatever it may be, on the sender 103, a selector 104 is adjusted 75 to extend the connection to the proper district or office in which the desired line terminates, whereupon the sender 103 is brought 80 into circuit over the talking wires 105, 106 of the selected trunk by way of the bottom contacts of sequence switch springs 107 and 108. The sequence switch springs shown in Fig. 1 are controlled by a well-known sequence switch (not shown), associated with selector 104, this sequence switch being moved into position 11 upon the adjustment of selector 104. The sequence switch springs 85 shown in Figs. 2 and 3 form a part of 90 sequence switches 215 and 303 associated with selector 200 and connector 302, respectively. Contact 109 of the sender is closed during the sending of impulses, and is opened for a short period after the sending 95 of a series of impulses. After the setting of selector 104, contact 109 is closed to start the selecting control operation for a selector 200. A fundamental or selecting circuit is closed from the minus pole of battery, 100 through the winding of a line relay 202, left-hand bottom contact of a sequence switch spring 203, left-hand top contact of sequence switch spring 204, resistance 205, conductor 105, terminal 110 and wiper 111 105 of selector 104, bottom contact of sequence switch spring 107, contact 109, winding of magnet 112, bottom contact of sequence

switch spring 108, wiper 113 and terminal 114 of selector 104, conductor 106, top contacts of sequence switch spring 206 and resistance 207 to the plus pole of battery. Line 5 relay 202 acts to close at its left-hand front contact a locking circuit by way of the left-hand top contact of sequence switch spring 203, so that this relay remains energized when its original path through sequence 10 switch spring 203 bottom opens. By reason of the closing of the right-hand front contact of relay 202 a circuit is closed from the plus pole of battery, bottom contact of sequence switch spring 209, right-hand armature 15 and front contact of relay 202, the left-hand top contact of sequence switch spring 210 and the winding of a trunk relay 211, to the minus pole of battery. Relay 211 closes a circuit from the plus pole of battery 20 through its right-hand armature and front contact, the left-hand contacts of sequence switch spring 214, and the winding of the power magnet of sequence switch 215 to the minus pole of battery, causing the sequence 25 switch to advance from normal to position 2. Relay 211 also closes a locking circuit for itself from the minus pole of battery through its winding, left-hand front contact and armature, resistance 217, test conductor 115, terminal 116 and wiper 117 30 of selector 104, resistance 118 and sequence switch spring 119, to plus battery.

opens the circuit of the lifting magnet 220 and closes a circuit from plus battery through sequence switch spring 209 bottom, its right-hand armature and back contact, the left-hand armature and back contact of 70 relay 230, the right-hand bottom and left-hand top contact of sequence switch spring 214 and the winding of the power magnet of sequence switch 215 to the minus pole of battery, to move the incoming sequence 75 switch 215 out of position 2 into position 3, in which position a trip magnet 231 is operated by the closure of a circuit from the minus pole of battery through the winding of this magnet and the right-hand contacts 80 of a sequence switch spring 232 to the plus pole of battery. Magnet 231 trips the desired set of brushes of selector 200. The elevating magnet 220 becomes deenergized when relay 202 reacts, and sequence switch 85 215 moves into position 3 and the selector and commutator brushes are arrested in their upward travel. After the sending out of the thousands impulses, contact 109 is again closed and the fundamental circuit established for again energizing relay 202, which then locks up in the above described manner. Upon the energization of relay 202 a circuit is closed from the plus pole of battery, through the bottom contact of sequence switch spring 209, the right-hand armature and front contact of relay 202, the left-hand 90 contact of sequence switch spring 222

In position 2 of the sequence switch 215 a circuit is closed from the plus pole of battery, through the bottom contact of sequence switch spring 209, the right-hand armature and front contact of line relay 202, the bottom contact of sequence switch spring 210 and the winding of magnet 220, to the minus pole of battery. Magnet 220 causes the brushes of selector 200 and commutator brushes 224, 225, 234, 250 to travel in a vertical direction. The selector brushes are adapted to engage contacts of a terminal bank and the commutator brushes, commutator plates 223, 226, 235 and 261 respectively. Plates 223 and 261 are composed of a conducting segment, and the other commutator plates of conducting and nonconducting segments. The sender stepping relay 112 is intermittently shunted, plus battery being connected to the right-hand top contact of sequence switch spring 203 through left-hand top contact of sequence switch spring 222, conducting segment 223, commutator brushes 224 and 225, and interrupter segment 226. The number of nonconductive segments traversed by the commutator brush 225 on plate 226, before the fundamental circuit is opened at 109, is determined in this instance by the setting of the thousands register.

35 contacts of the sequence switch spring 233 and the winding of power magnet 215 to the minus pole of the battery, for moving the sequence switch from position 3 into position 4. In this position of the sequence switch a circuit is closed from the minus pole of battery through the winding of the elevating magnet 220, bottom contact of sequence switch spring 210, the front contact and right-hand armature of relay 202 and the bottom contact of sequence switch spring 209 to the plus pole of battery. Under the control of magnet 220 the tripped selector brushes and the commutator brushes are moved in a vertical direction for selecting the desired group of trunks. The stepping magnet 112 of the sender is again intermittently shunted during the upward travel of the brushes, plus battery being connected through the upper left-hand contact of sequence switch spring 222, conducting segment 223, commutator brushes 224 and 234, commutator segment 235 and the right-hand bottom contact of sequence switch spring 203. After the selector has been adjusted, contact 109 is again opened, causing the deenergization of line relay 202, whereupon a circuit is closed from the plus pole of battery, through the bottom contact of sequence switch spring 209, right-hand ar-

40 45 50 55 60 65 70 75 80 85 90 95 100 105 110 115 120 125

Upon the opening of the fundamental circuit at 109 and the sending out of the last 65 impulse over plate 226 line relay 202 reacts, mature and back contact of line relay 202, the left-hand armature and back contact of relay 230, the right-hand bottom and left- 120

hand top contact of sequence switch spring 214, and the winding of the power magnet of sequence switch 215 to the minus pole of battery 216, for moving the sequence switch 5 out of position 4 into position 5. When relay 202 reacts and sequence switch 215 leaves its fourth position, the circuit of magnets 220 and 231 is opened and the selector brushes are arrested on the desired group of 10 trunk terminals. A circuit is now closed from the minus pole of battery, through the left-hand winding of test relay 230 and the left-hand top and right-hand bottom contacts of sequence switch spring 232 to the 15 plus pole of battery. Relay 230 becomes energized and, by attracting its left-hand armature, closes a circuit from the plus pole of battery through the bottom contact of sequence switch spring 209, right-hand armature 20 and back contact of line relay 202, left-hand armature and front contact of relay 230, the left-hand contacts of sequence switch spring 233, and the winding of the power magnet of sequence switch 215 to the 25 minus pole of battery, for moving the sequence switch out of position 5 into position 6.

In position 6 of the sequence switch, a circuit is closed from the minus pole of battery, through the winding of elevating magnet 220, the bottom contact of sequence switch spring 210, the left-hand front contact and armature of relay 230, the right-hand back contact and armature of relay 202 30 and the bottom contact of sequence switch spring 209 to the plus pole of battery. Magnet 220 causes the selector brushes to hunt over the terminals of the selected group of trunks. As long as brush 236 of selector 200 35 travels over the terminals of busy trunk conductors 301, *i. e.*, over trunks on which full plus battery potential exists and which lead to final selector switches 302, the associated sequence switches of which are in an off- 40 normal position, the test relay 230 finds a circuit from plus battery, through sequence switch spring 304, the right-hand back contact and armature of relay 305, resistance 306, conductor 301, selector brush 236, resistance 237, (or from plus battery, through the 45 top contacts of sequence switch spring 222 of other selectors), the right-hand armature and front contact of relay 230, the bottom contact of sequence switch spring 238 and the right-hand winding of relay 230 to the minus pole of battery. As soon, however, as selector 200 reaches the terminal of an idle trunk conductor 301, no such circuit is 50 found for relay 230, and this relay becomes deenergized, opening at its left-hand armature the energizing circuit of magnet 220, and closing a circuit from the minus pole of battery through the winding of the power magnet of sequence switch 215, the left-hand 55 top and right-hand bottom contacts of sequence switch spring 214, the back contact and left-hand armature of relay 230, the right-hand back contact and armature of relay 202, and the bottom contact of sequence switch spring 209, to the plus pole 60 of battery, for moving sequence switch 215 into position 7. In this position of the sequence switch, the fundamental circuit will again be closed for causing the energization of relay 202, which closes at its right-hand armature and front contact a circuit through the left-hand contacts of sequence switch spring 233 for sequence switch 215 and moves the same into position 8. In position 7 of the sequence switch, the test terminal of the selected trunk is rendered busy by a plus battery connection through the top contacts of sequence switch spring 222, resistance 237 and selector brush 236. 65

In position 8 of the sequence switch, line relay 202 remained energized by a locking circuit closed through its left-hand front contact and armature and the left-hand top contact of sequence switch spring 203. This relay further closes a circuit from the minus pole of battery through the winding of line relay 306, left-hand bottom and right-hand top contact of sequence switch spring 307, trunk conductor 308, brush 240 of selector 200, the right-hand top contact of sequence switch spring 210, the right-hand front contact and armature of relay 202 and sequence switch spring 209 to the plus pole of battery. Relay 306 becomes energized and closes a circuit from plus battery through its left-hand armature and front contact, the right-hand top and left-hand bottom contacts of sequence switch spring 310, and the winding of relay 305 to the minus pole of battery. Relay 305 upon energization, 70 closes a circuit from plus battery, through its left-hand armature and front contact, the right-hand top contact of sequence switch spring 311, and the power magnet of sequence switch 303 to the minus pole of battery, for moving this sequence switch out of its normal position into position 2. In position 2 of the sequence switch 303, relay 306 is maintained energized by a locking circuit closed from the minus pole of battery, through its winding, top contact of sequence switch spring 312, the right-hand front contact and armature of relay 306 and the top contacts of sequence switch spring 307 to plus battery at sequence switch spring 75 209. In this position of the sequence switch, a circuit is closed from the minus pole of battery through the winding of magnet 313, bottom contact of sequence switch spring 312, the right-hand armature and front contact of relay 306, the top contacts of sequence switch spring 307, and then in parallel with the circuit of relay 306 to the plus pole of battery at sequence switch spring 209. Magnet 313 moves the connector and 80 85

the associated commutator brushes in an upward direction. The sender stepping magnet 112 is intermittently deenergized and energized in substantially the same manner as will be described in connection with the units selection control of selector 302, the plus battery or ground impulses being sent to the sender from connector 302 under the control of commutator brushes traveling over interrupter segments.

After the sending of the first series of impulses from connector 302, the fundamental circuit is opened at contact 109. Relay 202 becomes deenergized and closes a circuit 15 through sequence switch spring 214 for driving sequence switch 215 out of position 8 into position 9. Relay 202 opens the circuit of relay 306, which in turn closes a circuit from plus battery, through its left-hand armature and back contact, left-hand top and right-hand bottom contact of sequence switch spring 310, and the power magnet of sequence switch 303 to minus battery for moving this sequence switch out of position 2 20 into position 3. The energizing circuit of magnet 313 is now opened at the front contact of relay 306 and sequence switch spring 312, and a magnet (not shown) causes now the tripping of the desired set of brushes of connector 302. Upon the next closure of the 25 fundamental circuit at contact 109, relay 202 becomes again energized and closes a circuit over the left-hand contacts of sequence switch spring 233 for moving sequence switch 215 out of position 9 into 10. The original energizing path of relay 306 is again established, and this relay again closes the circuit over the right-hand contacts of sequence switch spring 310 for driving sequence switch 303 into position 4. In 30 this position of the sequence switch, the energizing circuit for magnet 313 is again established over sequence switch spring 312, and the connector is moved to select the desired "tens." After the sending of impulses the fundamental circuit is again opened at 35 109 whereupon relays 202 and 306 react, the latter closing a circuit over the left-hand top and right-hand bottom contact of sequence switch spring 310, for driving sequence switch 303 out of position 4 into 5, and the former over sequence switch spring 214 for moving sequence switch 215 into position 11. In position 5 of sequence switch 40 55 303 the circuit of magnet 313 is again opened at the front contact of relay 306 and sequence switch spring 312. Upon the next closure of the fundamental circuit, relays 202 and 306 become energized, causing the 60 driving of sequence switches 215 and 303 into positions 12 and 6, respectively. The elevating magnet 313 is again energized, sequence switch spring 312 being closed. During the upward travel of the selector brushes, 65 the stepping magnet 112 of the sender is in-

termittently shunted, plus battery being connected through the left-hand bottom contact of a sequence switch spring 318, a conducting segment 315, commutator brushes 314 and 316, interrupter segment 317, the right-hand top contact of sequence switch spring 320, the right-hand top contact of sequence switch spring 321, trunk conductor 322, and the left-hand contacts of sequence switch spring 204, in the same manner as 75 was described with the adjustment of selector 200. After the last series of impulses have been sent back to the sender, contact 109 is again opened and relays 202 and 306 become deenergized, causing the stepping of sequence switches 215 and 303 into positions 13 and 7, respectively, and the opening of the circuit of magnet 313. Upon the sending out of the last series of impulses, the sequence switch controlling springs 107, 108 80 and 119 are moved out of position 11 into position 14, whereupon a circuit is closed from ground at repeating coil 120, through 107, 111, 110, 105, 204, 203 and 202 to 85 grounded battery. 90

Relay 202 upon energization closes the driving circuit through sequence switch spring 233 for moving sequence switch 215 out of position 13 into position 15, whereupon the circuit of relay 202 is opened at 95 204. Relay 306 is again energized by a circuit closed from the minus pole of battery, through its winding, left-hand bottom and right-hand top contact of sequence switch spring 307, conductor 308, brush 240, contact 100 241 of relay 242, the right-hand contacts of sequence switch spring 204, conductor 105, terminal 110, wiper 111 and the top contact of sequence switch spring 107, to ground at repeating coil 120. Relay 306 upon energization, 105 closes a circuit through the right-hand contacts of sequence switch spring 310 for driving sequence switch 303 out of position 7 into position 8, in which position a circuit is closed from ground, through the high resistance winding of a marginal test relay 323, the bottom contacts of sequence switch spring 324, the low resistance winding of relay 323, sequence switch spring 325, test wiper 326 of connector 302, and the 110 winding of a cut-off relay 330, associated with the called line to grounded battery. Supposing that the called line is idle, and therefore that full battery potential exists on the multiple test terminals thereof, the 115 above traced circuit causes the energization of test relay 323, which in turn closes a locking circuit for itself from ground, through the right-hand armature and back contact of relay 331, and its upper armature, front contact and low resistance winding. Relay 323 closes a circuit from plus battery through the left-hand armature and back contact of relay 331, the lower armature and front contact of relay 323, the right-hand bottom contact of relay 323, the right-hand bottom con- 120 125 130

5 tact of sequence switch spring 311 and the winding of the power magnet of sequence switch 303, to minus battery, and the sequence switch is moved out of position 8 and through position 14 into position 16, in which position the incoming line 308, 322 is extended through sequence switch springs 307 and 321 and connector brushes 332 and 333 to the called line.

10 In position 14 of sequence switch 215 a circuit is closed from the plus pole of battery through the left-hand top contact of sequence switch spring 222, conducting segment 223, commutator brushes 224 and 250, 15 conducting segment 251, the top contact of sequence switch spring 238 and the right-hand winding of the test relay 230 to the minus pole of battery, and another circuit from plus battery through the bottom and 20 left-hand top contacts of sequence switch spring 232 and the left-hand winding of relay 230 to the minus pole of the battery. This relay becomes energized and when sequence switch 215 is moved to position 15, 25 a circuit is closed from the plus of battery through the top contacts of sequence switch spring 222, the right-hand armature and front contact of relay 230, the right-hand bottom contact of sequence switch spring 252 and the power magnet of sequence switch 215 for moving this sequence switch into position 16, whereupon relay 230 becomes deenergized.

30 A circuit is now closed from the minus pole of battery, through the top contact of sequence switch spring 209, the right-hand armature and back contact of relay 202, left-hand armature and back contact of relay 230, the right-hand contacts of sequence switch spring 214, windings of relays 243 and 242, contact 244 of relay 245, sequence switch spring 246 and trunk conductor 105 to ground at repeating coil 120. Only relay 242 becomes energized, a shunt existing 35 around the winding of relay 243 from the armature and back contact of relay 247, the back contact and armature of the relay 243, the winding of this relay, and back to the armature and back contact of relay 247. 40 45 50 Ringing current is applied to the called line, a circuit being closed from ground through an alternating ringing current source 254, the winding of relay 247, sequence switch spring 255, the lower front contact and armature of relay 242, the calling subscriber's loop, and back to ground through the upper armature and contact of relay 242. As soon as the subscriber at the called station removes his receiver from the switchhook, relay 247 becomes energized, and by opening the shunt around the winding of relay 243, causes the energization of this relay, which in turn closes at its front contact a shunt around the winding of relay 242. Relay 242 becomes deenergized and disconnects

55 the ringing current from the called line. As a further result of the response of the called subscriber, supervisory relays 256 and 121 become energized, and the former, by attracting its armature, connects relay 245 in 70 parallel with relay 243, which will be maintained energized during conversation by a circuit extending from ground through the armature and front contact of relay 245, the front contact, armature and winding of 75 relay 243, the right-hand contacts of sequence switch spring 214, the back contact and left-hand armature of relay 230, the right-hand back contact and armature of relay 202, and the top contact of sequence switch spring 80 209, to the minus pole of battery.

85 When sequence switch 303 moved through position 15 into position 16, a circuit was closed from ground through sequence switch spring 334, the winding of relay 331, sequence switch spring 325, connector wiper 326 and the winding of relay 330 to the minus pole of battery. Relay 331 became energized and, by attracting its right-hand armature, closes a locking circuit for itself 90 and opens the circuit of relay 328. The called line is held by this circuit closed through relay 331.

95 Upon the restoration of the receiver at the called station 300, relays 121, 256, 245 become deenergized. Relay 121 actuates a well-known supervisory signal (not shown), whereupon the operator causes the restoration of selector 104, and the sequence switch associated therewith. The locking circuit of 100 relay 211 is opened thereupon, and this relay, by releasing its right-hand armature, closes a circuit from the plus pole of battery through its right-hand armature and back contacts, the left-hand top contact of sequence switch spring 252, and the winding of the power magnet of sequence switch 215 to the minus pole of battery for driving this sequence switch out of position 16 through 105 position 17 into position 18. In this position of the sequence switch a circuit is closed from the minus pole of battery through the winding of down magnet 257, and the bottom contacts of sequence switch spring 260 to the plus pole of battery. Under the control of magnet 257, selector 200 is restored to normal, whereupon a circuit is closed from the plus pole of battery through the left-hand top contact of sequence switch spring 222, conducting segment 223, commutator brushes 224 and 234, conducting segment 261, the left-hand bottom contact of sequence switch spring 252, and the winding of the power magnet of sequence switch 215 to the minus pole of battery for driving 110 sequence switch 215 out of position 18 into its normal position. Upon the release of selector 200 the locking circuit of relay 305 is opened and this relay closes a circuit from 115 plus battery through its left-hand armature 120 125 120

and back contact, the left-hand top contact of sequence switch spring 311, and the winding of the power magnet of sequence switch 303 to the minus pole of battery for driving 5 the sequence switch out of position 16 and through position 17 into position 18. A circuit is closed from the minus pole of battery through the winding of magnet 335, and the right-hand top and left-hand bottom 10 contacts of sequence switch spring 318 to plus battery. Under the control of magnet 335 connector 302 is restored to normal. When connector 302 reaches its normal position, a circuit is closed from plus battery 15 through the left-hand bottom contact of sequence switch spring 318, conducting segment 315, commutator brushes 314 and 336, conducting segment 337, the left-hand bottom contact of sequence switch spring 311, 20 and the power magnet of sequence switch 303 to the minus pole of battery, and this sequence switch is moved out of position 18 into its normal position. Relay 331 thereupon becomes deenergized. All the apparatus employed in the building up of the connection is restored to normal, the operator having removed her plug 101 upon the receipt of a well-known clearing-out signal (not shown) controlled by relays 121 and 25 30, 122, the latter being deenergized upon the restoration of the receiver at the calling station. If the called subscriber's line is found busy, relay 323 will not become energized, due to the lack of full battery potential on 35 the test terminal of this line. Relay 306 becomes energized by a circuit from the minus pole of battery, through its winding, the left-hand top contact of sequence switch spring 321 (sequence switch 303 being in position 40 8), the right-hand bottom contact of sequence switch spring 320, the lower back contact and armature of relay 323, and the left hand back contact and armature of relay 331 to plus battery. Upon the energization of relay 306 a circuit is closed from plus battery through the left-hand armature and front contact of this relay, the right-hand contacts of sequence switch spring 310, and the power magnet of sequence switch 303 to 45 50 the minus pole of battery for moving the sequence switch out of position 8 and into position 14, in which position a circuit is closed from the minus pole of battery through the winding of the magnet 335, sequence switch spring 340, the lower armature and back contact of relay 323, and the 55 left-hand back contact and armature of relay 331 to plus battery. Under the control of magnet 335 the switch is released to normal. Upon the release of this switch, plus battery is connected through brush 336, segment 337, and the left-hand bottom contact of sequence switch spring 311 to the power magnet of sequence switch 303, and this sequence switch is moved into position 17, in 60 which position a busy tone signal is applied to the calling subscriber's line from a signaling source 341, through sequence switch springs 342 and 324. The calling subscriber, by hanging up his receiver, causes the operator to release selector 104 and the associated sequence switch, whereupon selector 200 and sequence switch 303 are restored to normal in the above described manner.

What is claimed is:

1. In a telephone exchange system, the combination with a plurality of lines, a plurality of automatic power-driven switches for interconnecting said lines, driving circuits for said switches, and a sender for controlling the operation of said switches by means of revertive impulses, of a single relay to coöperate with said sender for directly controlling the driving circuit of each switch in succession. 75

2. In a telephone exchange system, the combination with a plurality of lines, a plurality of automatic power-driven switches for connecting said lines, driving magnets for said switches, circuits for energizing said magnets, and a sender for controlling the operation of said switches by means of revertive impulses, of a single relay coöperating with said sender and controlling at a front contact the magnet energizing circuit of each switch in succession. 80

3. In a telephone exchange system, the combination with a plurality of lines, a plurality of automatic switches for interconnecting the same, and a fundamental circuit comprising a stepping relay and a control relay for jointly supervising the operation of each of said switches, of a commutator associated with each switch for intermittently shunting said stepping relay but maintaining energized said control relay during the advance of its associated switch. 85

In witness whereof, we hereunto subscribe our names this 8th day of September A. D., 1915.

FRANK N. REEVES.
ALBEN E. LUNDELL.
